UNITED STATES PATENT OFFICE.

ANSON C. MILLS, OF JACKSON, MICHIGAN, ASSIGNOR TO JACKSON FENCE COMPANY, OF JACKSON, MICHIGAN, A CORPORATION OF MICHIGAN.

FENCE-MACHINE.

1,319,162.

Specification of Letters Patent.

Patented Oct. 21, 1919.

Application filed January 11, 1917. Serial No. 141,903.

To all whom it may concern:

Be it known that I, ANSON C. MILLS, a citizen of the United States, and resident of Jackson, in the county of Jackson and 5 State of Michigan, have invented certain new and useful Improvements in Fence-Machines, of which the following is a specification.

My invention relates to fence making machinery wherein staple forming, staple guiding and staple driving devices are associated with wire feeding and fabric moving devices, the whole forming an automatic machine for producing stiff stay, staple 15 locked wire fencing.

One of the principal objects in the construction of the present machine is to provide means whereby the staple which is used to unite the strand and stay wires of the 20 fence at their intersections shall be formed and driven in the same plane without necessitating the turning of the staple on either its transverse or longitudinal axis between the forming and driving positions, and at 25 the same time secure the advantage of close spacing. In the present arrangement, the staple forming devices are located in juxtaposition and permanently located in equally spaced relation; the driving elements are, however, movable, in order to 30 change the spacing of the line wires as desired, the forming and driving mechanisms being connected by a guide, along which the staples are fed by gravity. Inasmuch as the 35 wire on which the staples are formed is fed to the staple forming machine from beneath, a separate wire being provided for each staple former, it will be seen that one or more of the staple formers may be disconnected 40 without interfering in any manner with the operation of the remainder of the formers. This, therefore, provides for independence in the matter of the spacing of the line wires, as well as the control of the number 45 of such wires. It is intended that the machine shall be equipped with the maximum number of staple forming devices which may at any time be required, and that these devices are permanently secured 50 in the machine, all of the devices being actuatable by a single reciprocating element, and wire feeding means being provided for each staple former. The staple driving means are, however, independently mounted and 55 adjustable to suit different spacings, the

staple forming devices which are utilized being connected to the driving devices by means of an inclined guide.

A further object is to provide staple forming mechanism which shall be simple and 60 adaptable for rigid design, so as to reduce the probability of disarrangement or breakage. It will be understood that in the construction of a fence such as referred to a 65 number of staple forming devices are provided corresponding to the number of strands of wire in the fence, and that as economy in cost of production is dependent upon practically uninterrupted operation, the disarrangement of one staple forming 70 mechanism increases the cost of production, due to the fact that the feeding mechanism must be stopped. For this reason simplicity and ease of repair are essential.

A further object is to provide a staple 75 forming mechanism wherein the forming and formed staples are constantly exposed, so that any defects are readily observed and corrected.

A still further object is to provide staple 80 forming mechanism wherein a supply of staples is maintained in reserve behind the staple being set or driven.

The invention will be more readily understood upon reference to the accompanying 85 drawings, wherein—

Figure 1 is a sectional elevation of a machine constructed in accordance with my invention, the section being taken on the line 1—1 of Fig. 3;

Fig. 2 is a partial plan view of the machine;

Fig. 3 is an end elevation taken at right angles to the view shown in Fig. 1;

Fig. 4 is a section on the line 4—4 of Fig. 95 3 somewhat enlarged over that shown in Fig. 1;

Fig. 5 is an elevation, partly in section, of the staple forming device;

Fig. 6 is a plan view, partly in section, the 100 section line being taken on the line 6—6 of Fig. 5;

Fig. 7 is a section on the line 7—7 of Fig. 6;

Fig. 8 is a view of a staple such as employed, and

Fig. 9 is a view of a section of completed fence.

Referring more particularly to the drawings, it will be seen that I provide a frame 110

10, within which is mounted a main driving shaft 11. An eccentric 12, provided at each end of the machine, provides means for vertically reciprocating the cross head 13, which 5 carries a plurality of drivers, or staple setters, 14. These drivers coöperate with the die member 15, which is rigid with the bed 16 of the machine and with the die member 17, which is movable with the recipro- 10 cating member 18. The line or strand wires of the fence are fed vertically upward and are indicated at 19. The stay or cross wires 20 are fed transversely of the strand wires, the two wires being joined 15 at their intersection by means of a staple such as indicated in Fig. 8. A sample of the fence in its finished condition is indicated in Fig. 9. The staples are supplied to the dies 15 by means of guides or slide- 20 ways 21, connecting the staple forming machine 27 with the staple driving means. It will be noted, by reference to Fig. 1, that the slideways 21 are inclined horizontally and, by reference to Fig. 2, that they may 25 be deflected laterally, as desired, to accommodate different line spacings in the fence. It will be further noted, by reference to Figs. 2 and 3, that I have provided ten staple forming machines which are per- 30 manently located in equally spaced relation, thus providing for the formation of a fence of maximum size or height. It will be understood that the top and bottom strand wires are united to the stay wires by coiling 35 the ends of the latter about the line wires. When, however, a fence having a less number of strand wires is to be formed, only the required number of staple forming machines are placed in operation, the remainder op- 40 erating idly, no wires being fed thereto for the formation of the staple.

The staple former which I prefer to employ is of novel construction and comprises a support 23 and the base 24, which is a 45 portion of the frame of the machine. On the support is mounted the anvil 25, around which the wire staples are bent, the shear blade 26, a head 27 providing a mounting for the staple former and a rack bar 28 50 which actuates the staple former. The rack bar 28, as best shown in Figs. 4 and 5, is mounted in a recess in the support 23 and held in place by means of a plate 29. The teeth of the rack bar are upon the upper 55 face thereof and engage a pinion 30 rigid with a shaft 31 mounted in the head 27. On the opposite end of the shaft, and mounted within a circular recess is a disk 32, best shown in Fig. 5, to one face of which disk 60 is fixed a pin 33 having a freely rotatable sleeve 34 thereon. The pin is located near the periphery of the disk and is adapted for travel through an arc of substantially 180°, then to return to its original position.

Mounted immediately beneath the disk 32 65 is the stationary shear blade 35. This element is mounted between adjacent walls 36, 37, of the head and is held against longitudinal displacement by means of a dowel 38. As a matter of economy, I provide a 70 cutting edge, which, in the present instance, is in the form of an open-sided aperture 39 in both ends of the stationary shear. Located beneath the stationary shear blade, 75 is the movable shear blade 26, which is likewise mounted upon the dowel 38 and is provided at one end with the transverse aperture 40, through which the wire passes. An aperture 41, through the support 23, and 80 a leading tube 42 comprise the means for directing the wire to the proper point. It will be understood that the movable shear blade 26 is adapted for oscillation on the dowel, such movement being caused by contact with a lug 43 fixed to the lower edge 85 of the rack bar 28. The shear blade 26 is returned to and held in normal inoperative position by means of the long coil spring 44, which is seated in a recess in the support 23. A plug 45 rests upon the top of the coil 90 spring, this element in coöperation with the plate 29 serving to confine the spring within the recess.

The anvil 25 is suitably secured to the support 23, with the upper inner end of 95 the anvil projecting into the arc of rotation of the forming finger 33, 34. The outer end of the anvil is notched, as at 46, and in this notch the guide 21 may be fitted.

It will be noted, by reference to Figs. 2 100 and 3, that while provision has been made for the maximum number of staple forming machines, yet only eight of the ten are operatively connected to the fabric forming machine. The line wire spacing of the 105 fence to be woven is indicated by the location of the dies 15. The guides or slideways 21 are deflected laterally as required to connect the staple forming machine to the staple driving guides. By this arrangement 110 it will be seen that the staple is formed in a substantially vertical position and maintained in that position during its travel by gravity to the dies, whereupon it is driven 115 in the same position. Not only is this result secured, but I am enabled to make as close spacing of the line wires of the fence as desired without regard to the spacing of the 120 staple forming devices.

The means for causing the reciprocation 120 of the rack bar which actuates the staple forming devices may include the crank 46, connected by means of a link 47 to the rack bar. The lever 46 is mounted on a shaft 48, which carries on its opposite end a second 125 lever 49. Motion is imparted to this lever through the medium of the coil spring 50, carried by the cross head 13. A limited free-

dom of movement is permitted which allows a slight dwell in the action of the staple forming devices.

It will be noted that the dies 15 are 5 mounted for ready adjustment in the frame member 16, a corresponding adjustment being permitted of the driver 14 in the cross head 13.

Obviously, as far as the broad disclosure 10 is concerned, the forms of the elements may be changed without departure from the spirit of my invention. Such modifications as are within the scope of my claims I consider within the spirit of my invention.

15 I claim:

1. In a machine for uniting the strand and stay wires of a fence, the combination of staple setting mechanisms at the junctions of said wires, staple forming mechanisms 20 located adjacent to the setting mechanisms and positioned to form staples with their legs in a plane substantially parallel to the plane of the strand wires, means for directing a staple wire to each staple forming 25 mechanism substantially in a line with the fence strand wires, and means for conducting staples from the forming to setting mechanisms and for driving the staples with their legs in a plane substantially parallel 30 to that in which the staples were formed.

2. In a machine for uniting strand and stay wires of a fence, the combination of 35 staple setting mechanisms at the intersections of said wires, staple forming mechanism, guides connecting said staple forming and setting mechanisms, the mechanisms being arranged to form and set the staples in substantially parallel planes, said staple forming mechanisms being mounted in a 40 fixed position and said setting mechanisms being mounted for adjustment to different strand wire spacings.

3. In a fence machine, the combination of 45 staple forming mechanisms, staple driving mechanisms, said staple forming mechanisms being located in equally spaced relation, said driving mechanisms being spaced according to the strand wire spacing of the fence the space between said staple 50 forming mechanisms being greater than the space between certain of the staple driving mechanisms, means for directing separate wires to each of said staple forming mechanisms and a single operating means

for all said staple forming mechanisms the 55 staples being formed and set in substantially parallel planes, substantially as described.

4. In a fence machine, the combination of 60 staple forming mechanisms, means for directing a separate wire to each of said forming mechanisms, said wires being directed in a line substantially parallel to the strand wires of the fence being formed, staple driving mechanism, means for adjusting 65 said driving mechanism to correspond to the spacing of the line wires of the fence to be constructed, a guide or slideway between said forming and driving mechanisms and means for operating said forming and driving mechanisms, the arrangement being such 70 that said staples are formed and driven in substantially parallel planes, substantially as described.

5. In a machine for uniting the strand and 75 stay wires of a fence, the combination of a staple former and a staple setter, the strand wires of the fence being directed substantially vertical and the wires for supplying the staple formers being directed in a line substantially parallel to said strand wires, 80 the staples being formed and set in parallel planes, and a substantially straight inclined sidebar between the forming and setting devices the staples being formed in such position as to straddle said sidebar and being 85 delivered to the setter without change in such position, substantially as described.

6. In a machine for uniting the strand and stay wires of a fence, the combination of 90 staple forming and setting mechanism, the strand wires of the fence being directed in a substantially vertical line past the setting mechanism, the individual wires supplied to the staple forming mechanism being directed in a line substantially parallel 95 to the strand wires, said staple forming mechanism including an anvil over which the staples are bent, and a slideway which acts as a continuation of said anvil and extends in substantially a straight line 100 to the staple setting mechanism, substantially as described.

Signed at Chicago, Illinois, this 12th day of December, A. D. 1916.
